(57) **CLAIM**

The ornamental design for a pair of infant shoe soles, as shown and described.

DESCRIPTION

FIG. 1 is a rear perspective view showing a left component of a pair of infant shoes, showing our design;

FIG. 2 is a front perspective view of the infant shoe of FIG. 1;

FIG. 3 is a bottom view of the infant shoe of FIG. 1;

FIG. 4 is a top view of the infant shoe of FIG. 1;

FIG. 5 is a left side view of the infant shoe of FIG. 1;

FIG. 6 is a right side view of the infant shoe of FIG. 1;

FIG. 7 is a front view of the infant shoe of FIG. 1; and,

FIG. 8 is a rear view of the infant shoe of FIG. 1.

The drawings show the design of an infant shoe sole suitable for being worn on the left foot. The ornamental design also includes the mirror images of drawings, i.e., the design of an infant shoe sole suitable for being worn on the right foot.
